UNITED STATES PATENT OFFICE.

RUFUS HERRICK DORN, OF LOS ANGELES, CALIFORNIA.

MITER-BOX.

SPECIFICATION forming part of Letters Patent No. 733,823, dated July 14, 1903.

Application filed October 19, 1901. Serial No. 79,318. (No model.)

To all whom it may concern:

Be it known that I, RUFUS HERRICK DORN, of the city of Los Angeles, in the county of Los Angeles, in the State of California, have 5 invented certain new and useful Improvements in Miter-Boxes, of which the following is a full, clear, and exact description or specification, reference being had to the annexed sheets of drawings and to the letters marked 10 thereon.

The improvements in miter-boxes which constitute my present invention are further developments of certain constructive and operative features of that particular kind of miter-box for which Letters Patent have been granted to me, the said RUFUS HERRICK DORN, on or about the 18th day of July, 1900, No. 651,457, and in respect of which my present improvements consist, as hereinafter 15 described.

Upon the annexed sheets of drawings, Figure 1 is a plan of the lower part of the circular miter-box, showing such of my improvements applied thereto as are visible in a plan 20 of the circular table thereof. Fig. 2 is an inverted plan of the under parts of my improved miter-box. Fig. 3 is a front elevation of my improved miter-box. Fig. 4 is a rear elevation of the right-hand and part of the left-hand back or movable leaf of my improved 25 circular miter-box, showing the ring attachments. Fig. 5 is a plan of the attachment of the leaf shown at Fig. 4 to the central pivot at the under side of the table of my improved 30 miter-box. Fig. 6 is a transverse section of my improved miter-box, taken in the plane of the saw upon the line $x x$, Fig. 1, by which molding or other lumber is cut in my improved miter-box and which plane corresponds to that occupied by the section of the 35 saw shown at Fig. 3. Fig. 7 is an edge elevation of a removable supporting inclined stop used in connection with the other movable stops of my improved miter-box, and this removable stop is for the purpose of giving support to the rear face of "half-moldings" when such half-moldings are placed in the miter-box to be cut at an angle from the rear face 40 thereof. Fig. 8 is a plan of the removable stop shown in elevation at Fig. 7. Fig. 9 is a front elevation of an ordinary crosscut-saw adapted under my present improvements for

being used in my improved miter-box. Fig. 10 is a plan of the handle end of this crosscut-saw so adapted. Fig. 11 is a front elevation of the front slide in which said crosscut-saw so adapted operates. Fig. 12 is an elevation of the rear slide of my improved miter-box, wherein said crosscut-saw so adapted is operated. Fig. 13 is a transverse section of 55 the outward end of the crosscut-saw and the parts applied thereto for adapting said crosscut-saw to be operated in my improved miter-box and which section is taken upon the line $y y$, Fig. 9.

Upon Figs. 1, 3, and 6 the circular table of my improved miter-box is marked A A, and the two angularly-movable leaves of the said miter-box are marked B B', respectively. At the center of the under part of the circular 60 table A A of my improved miter-box there is formed a strong pivot C, Fig. 6, and upon this pivot are carried each of the two rings D and D', to an arm E, projecting from each side, of which and shown more particularly 65 at Figs. 4 and 5 each leaf B and B' is respectively carried or attached thereto in the manner now to be described. Each arm E of each ring D and D' is so shaped, as shown at Fig. 4 more especially, that the upper ends thereof 70 pass up into the circular or segmental openings F, formed in the circular table A A, as shown more particularly at Figs. 1, 2, and upon this upraised part of each arm E each of the backs B and B' is respectively carried 75 by being attached thereto by means of screws a a, which pass through the vertical bracket, (marked G in Figs. 1, 3, 4, and 5,) so that the vertical brackets G each pass up through an opening in the flange H at the rear of each 80 back or leaf B or B', which rests close down upon the flat portion of the arm E, while the upright portion of the arm E constitutes an ample vertical support for maintaining each back or leaf B or B' in a rigid vertical position, such as is required for the movable 85 backs or leaves of a miter-box, and with the view of simplifying generally the construction of these parts of my improved miter-box I mount the rings D and D' (more especially 90 shown at Fig. 6) upon one and the same pivot C, through which a central screw or bolt I is passed, as shown at Fig. 6, which by means 95 of the nut J and washer K, placed on the 100

lower end thereof, maintains not only the two rings D and D' and the leaves or backs B and B' in operative relationship with each other and with the miter-box generally, as is well understood, but which central pivotal attachment also carries the circular ring-stand L, upon which the entire miter-box rests, and is capable of being turned around upon into any angular position required and to be fastened or screwed in said angular position in the manner hereinafter described. The circular stand L is constructed with arms L', as more particularly shown at Figs. 2 and 6, and at or near the periphery of its under side there are placed pointed feet M, by which the entire miter-box is supported upon the bench or other supporting-surface whereon it is used for cutting miters, as is well understood.

In order to fasten the miter-box in any angular position whereat it is or may have been turned upon its vertical axis or pivot C, as hereinbefore described, a vertical set-screw N is passed through a tapped hole in the rear part of the circular table A A, as shown at Figs. 1 and 6, and this set-screw on being tightened by turning it in such direction that its lower end presses upon the upper part of the circular stand L L causes a part of the edge of that circular stand L L to be pressed against the inturned lip of a lug or bracket O, formed upon the under side of the circular table A A, and in this manner the circular table A A and the circular stand L L become so tightly pressed together at this point of both that so long as the set-screw N is thus caused to press downward upon the circular stand L L the miter-box becomes securely held in any angular position required, while by releasing the pressure of the set-screw N—that is to say, by unscrewing it at the pressure contact with the circular stand L L—is released and the entire miter-box then becomes free to be turned around upon the pivot C into any other angular position required.

A further part of my present improvements consists of a modified form or construction of the lever P by which each leaf B or B' is retained in the notches Q at the under side of the table of the miter-box for holding the leaves or backs B or B' in any required angular position, and this lever P is constructed with a rearward-projecting arm P', as shown more particularly in the rear elevation of the leaf or back B at Fig. 4. This lever P is pivoted upon a pin P'' and operated upon at the outer end of the arm P' by means of a spring R, fastened to the upper part of the opening S in the under part of the leaf or back, by which it passes over the stop T when the angular stop U is not fastened thereon. In Figs. 1, 3, 6, 7, and 8 of the drawings the action of the spring R is to press upward against the under part of the arm P', and thereby to maintain the lever P in such position that the retaining-catch P'', forming the lower end thereof, is held in any one of the notches

Q Q Q in the under part of the circular table A A, while by applying the hand to the upper part of either lever P and by pressing either lever P until the upper part thereof comes into contact with the projecting lug V (shown at Fig. 4) either of the retaining-catches P'' is moved out of any of the notches Q Q Q and in which position of the retaining-catch either of the leaves or backs B or B' is free to be rotated to any other angle required. By releasing the hand from either of the levers P P the retaining-catch P'' enters into and engages with any notch Q and again retains either back or leaf B or B' in the requisite operative angular position. The supplementary stop U, which is used only for giving support to the rear of half-moldings when such half-moldings are being cut in my improved miter-box, consists simply of a flat piece of metal U, as shown in several of the figures, but more especially on a larger scale in Figs. 7 and 8, and which supplementary stop is constructed with a slot W at the lower flat end thereof, so that this part of the supplementary stop may be passed under the lower part of the thumb and finger screw T', and is thereby securely or firmly fastened to the stop in any required position to give support to the back or rear of a half-molding, as shown more particularly at Fig. 6.

It is to be understood that the saw used in this improved miter-box is an ordinary tenon-saw, such as is shown at Y in Fig. 3 and in dotted lines indicating its position in Fig. 6, but which is not shown in the other figures of the drawings, because such saw, being a feature or detail common to all miter-boxes, constitutes no part of my present invention.

As shown by Figs. 9 to 13, the crosscut-saw (marked X) is of the kind commonly used by carpenters, joiners, and others and is operated with an ordinary wooden handle, as shown more especially at Figs. 9 and 10. To adapt such a saw for being used in the slides of my improved miter-box after the manner wherein the tenon-saw (marked Y Y) is shown at Fig. 3 of the annexed drawings, I apply or adapt to an ordinary crosscut-saw X the back or frame, (marked Z.) This back or frame is held onto the saw X in the following manner: The back or frame is constructed at its outer end with a narrow opening b b, the width of which opening b b is sufficient to admit of the outer end of the saw passing thereinto, and the outer end of the saw X has formed in it the parallel notch c, (shown dotted in Fig. 9,) of a width equal to the diameter of the transverse pin d, which is situated in the opening b b, as shown more particularly in the transverse section, Fig. 13. By means of this pin d and the notch c in the saw the outer ends of the frame or back Z become united or held together, and at the rearward or handle end of the saw the back Z and the saw X are held together by means of the spring e, which is fastened to

oily vapors, as well as increasing and maintaining a uniform draft.

Having thus described my invention, what I claim, and desire to secure by Letters Patent, is—

- 5 1. A gaseous-fuel burner comprising a body having one or more transverse apertures, a longitudinal conical bore bisecting said apertures, and air-inlets communicating with the top and bottom portion of the bore, a generator-pipe arranged for attachment to an oil-supply pipe, a valved ejector connected with the generator-pipe held to discharge into the wide end of the conical bore in the body, as set forth.
- 10 2. A gaseous-fuel burner comprising a body having a series of transverse apertures and a cone-shaped longitudinal bore bisecting the transverse apertures, said body also having air-inlets that communicate with the conical bores, a generator-pipe arranged to connect with an oil-supply pipe, and an ejector-valve that discharges into the wide end of the conical bore in the body, for the purposes described.
- 15 3. A gaseous-fuel burner; comprising a body having one or more transverse apertures, a longitudinal bore bisecting said apertures and having air-inlets communicating with said longitudinal bore, a generator-pipe arranged for attachment to an oil-supply pipe, and a valved ejector connected thereto, the latter being positioned on the body to discharge therein at an acute angle to the longitudinal axis of the said bore, for the purposes described.
- 20 4. An improved oil-burner of the character described; comprising a body having a central longitudinal conical bore, a series of transverse apertures bisecting said bore, and a series of air-inlets in the top and bottom that communicate with the conical bore, a generator located on the top of the burner between the top air-inlets, a feed-pipe connected to one end of the generator and a valved ejector connected to the other end of the generator arranged to discharge the gaseous fuel at an angle against the wall of the conical

bore whereby to create a staggered flow of the said fuel through the conical bore, as specified.

5 5. A gaseous-fuel burner; comprising a body having a central longitudinal bore, transverse apertures bisecting said bore, and air-inlets communicating with the bore; of a detachable base member having rests for supporting the burner-body, said base having air-inlet passages and being wider than the body to provide lateral extensions, said extensions having longitudinal drip-collecting channels, a pocket into which said channels discharge and another channel for conveying the collections in the said pockets under the burner-body, for the purposes described.

6 6. In a burner as described; the combination with the body having a longitudinal bore, a series of transverse apertures bisecting the bore, and air-inlets communicating with the said bore; of the base 2, provided at one end with a drip-collecting pocket, its other end being extended under the feed or ejector valve, a central channel connecting the two pockets, said base also having its sides extended beyond the sides of the body and provided with drip-collecting channels that discharge into one of the end pockets, a generator-pipe and feed-pipe and a valved ejector connected therewith, the latter being held to discharge into the bore, as set forth.

7 7. In a burner of the character described; the combination with the body 1, having a central bore, lateral flues joined therewith and air-inlets communicating with the bore; of a generator-pipe detachably mounted lengthwise of and on top of the body, a feed-pipe detachably connected with one end of the generator-pipe, and a valved ejector connected with the other end of the ejector-valve, the latter including a needle-valve stem having an annular shoulder and a screw-cap joint with which the shoulder engages when the valve is turned back to the limit, for the purposes described.
